UNITED STATES PATENT OFFICE

EMMANUEL DOBROWSKY, OF NEW YORK, N. Y., ASSIGNOR TO MOTOR CAR ADVERTISING DEVICE CO., INC., OF NEW YORK, N. Y., A CORPORATION OF NEW YORK

VACUUM MOTOR

Original application filed May 9, 1927, Serial No. 189,956. Divided and this application filed August 29, 1928. Serial No. 302,821.

This invention relates to taxi advertising devices, an object of the invention being to provide a neat, attractive and ornamental device which can be conveniently located in a 5 taxicab, bus, or other vehicle, and which will display advertising matter or a plurality of advertisements in succession which can be readily seen by the occupants of the vehicle.

A further object is to provide a device of 10 this character having a suction motor operatively connected to the manifold of an internal combustion engine such as commonly employed on taxicabs, busses and the like.

This is a division of my application for 15 patent on taxi advertising device, filed May 9, 1927, Serial No. 189,956.

A further object is to improve upon the construction disclosed in my copending application Serial No. 41,819, filed July 6, 1925.

20 With these and other objects in view, the invention consists in certain novel features of construction and combinations and arrangements of parts, which will be more fully hereinafter described and pointed out in the 25 claims.

In the accompanying drawings—

Figure 1 is a sectional plan view of my improved motor and associated parts;

Figure 2 is a view in vertical longitudinal 30 section taken on the line 2—2 of Figure 1;

Figure 3 is a view in transverse section through a cylinder and the reciprocating frame, the view being taken on the line 3—3 of Figure 2;

Figure 4 is a view in longitudinal section 35 through the suction motor showing the same in connection with adjacent parts;

Figure 5 is a view similar to Figure 4, showing the parts in a different position;

Figure 6 is a fragmentary plan view of the 40 ratchet pawl 52 and its mounting;

Figure 7 is a view in front elevation, showing the valve controlling mechanism of the 45 suction motor;

Figure 8 is a view similar to Figure 7, showing the parts in a different position;

Figure 9 is a view in transverse section on 50 the line 9—9 of Figure 7;

Figure 10 is a view in elevation, somewhat

diagrammatically illustrating the operation of the ratchet pawl 52;

Figure 11 is a perspective view of the slide plate 23;

Figure 12 is a view partly in elevation and 55 partly in section showing my improved device in connection with a taxicab.

1 represents the casing of my improved 60 taxi advertising device, illustrated in detail in Figures 1 to 12, inclusive. This casing 1 is located in the upper front portion of the passenger compartment of a taxicab 2 or other analogous vehicle so that it may be readily seen by the occupants of the vehicle.

65 The suction motor A, shown in longitudinal section in Figures 4 and 5, includes a pair of aligned cylinders 15 and 16 open at the outer ends and secured to a central head 17. The open outer end of the cylinders 15 and 16 70 have central bearings 18 for piston rods 19, and said piston rods are secured to pistons 20 located in the respective cylinders 15 and 16.

A frame 21 is secured to the front of the 75 head 17 and has parallel rails 22 therein for the mounting and guidance of a sliding plate 23, shown in perspective in Figure 11.

The head 17 is provided with a pair of 80 transversely positioned valves 24 and 25, respectively. These valves 24 and 25 have longitudinal ports 26 and 27 in their respective ends. Blocks 28 are secured on the valves 24 and 25 intermediate their ends and are movable in recesses 29 in the head 17. These 85 blocks are cushioned at their ends to prevent noise of contact with the walls of the recesses, and coil springs 30 are located around the valves between the blocks and valves of the recesses, tending to move the valves in one 90 direction.

31 represents a manifold which is secured to the head 17 and is always in direct communication with the ports 26 in both of the valves 24 and 25. This manifold may be 95 connected by a pipe 32 with the manifold 33 of the engine 34 so as to establish suction in the pipe and manifold 31.

The valves 24 and 25 are adapted to project through the head opposite to the point of 100

attachment of the manifold 31 and have bevelled ends 35 which are adapted to be engaged in turn by the slide plate 23 above referred to.

5 The slide plate 23 has a longitudinal slot 36 therein receiving a pin or fixed guide member 37 on the head 17, and enlargements 38 are provided on the ends of the slide plate 23 which are alternately engaged by a pivoted arm 39 mounted in the frame 21. This arm 39 is pivotally mounted between its ends on the frame 21 and is connected at one end by a coil spring 40 to the frame 21.

15 It will be noted that this spring 40 is disposed parallel to the arm when the arm is in vertical position but when the arm is moved past vertical position or past dead center the spring will throw the arm to either of its extreme positions, and when the lower end 20 of this arm engages the respective enlargements 38 on plate 23 it will slide the same from one position to another.

25 When the plate is slid to one position, as shown in Figure 4, the valve 25 will be forced inwardly while the valve 24 will be permitted to project outwardly and be held in this position by its spring 30. When the valves are in the position shown in Figure 4 air is sucked through the port 26 of the valve 24, 30 drawing the piston 20 in the cylinder 15 toward the central head 17, at the same time, when the piston 20 in cylinder 16 moves outwardly, it will suck air into the cylinder through the port 27 in valve 25.

35 When the arm 39 is moved to a reversed position the position of the valves will be reversed and the operation will of course be reversed with respect to the pistons in the cylinders.

40 The piston rods 19 above referred to are secured to a rod frame 41 carrying the rings 42 mounted to slide on the cylinders 15 and 16, and these rings 42 have keyways 43 therein receiving keys 44 on the cylinders to prevent turning motion of the rod frame on the cylinders.

45 The rings 42 of the rod frame 41 have fingers 45 thereon, which are adapted to engage the ends of a sliding rod 46 mounted in the frame 21 and extending through a slot 47 in the arm 39. On this rod 46 a pair of spaced cushioned bumpers 48 is located and is adapted to engage the arm 39 and force it from one extreme position to a point beyond the dead center thereof when the spring 40 completes the throw of the arm to operate the plate 23 and shift the positions of the valves 24 and 25.

50 Various changes and alterations might be made in the general form of the parts described without departing from the invention and hence I do not limit myself to the precise details set forth but consider myself at 55 liberty to make such changes and alterations

as fairly fall within the spirit and scope of the appended claims.

I claim:

1. A suction motor, comprising a pair of aligned cylinders, a central head between the cylinders, pistons in the cylinders, a pair of spring-pressed valves located in the head and having ports in their respective ends, an outlet manifold connected to the head and communicating with the ports in one end of each valve, springs exerting pressure on the valves to move them in one direction, said valves having beveled ends projecting beyond the head, a sliding plate engaging the beveled ends of the valves and causing them to shift from one position to another, a pivoted arm, a spring engaging one end of the arm and adapted to throw the same from side to side after the arm has passed its dead center, enlargements on the plate engaged by the arm to shift the position of the plate, and means operated by the suction motor to move the arm.

2. A suction motor, comprising a pair of aligned cylinders, a central head between the cylinders, pistons in the cylinders, a pair of spring-pressed valves located in the head and having ports in their respective ends, an outlet manifold connected to the head and communicating with the ports in one end of each valve, springs exerting pressure on the valves to move them in one direction, said valves having beveled ends projecting beyond the head, a sliding plate engaging the beveled ends of the valves and causing them to shift from one position to another, a pivoted arm, a spring engaging one end of the arm and adapted to throw the same from side to side after the arm has passed its dead center, enlargements on the plate engaged by the arm to shift the position of the plate, a rod frame moved by the suction motor, a movable rod, bumpers on the rod adapted to engage and shift the position of the arm, and devices on the rod frame engaging the ends of the arm to cause the latter to move longitudinally first in one direction and then in the other.

EMMANUEL DOBROWSKY.
